UNITED STATES PATENT OFFICE.

GEORGE L. TRUESDELL, OF REDWOOD FALLS, MINNESOTA.

LOW-TENSION SPARK-PLUG.

1,263,005.

Specification of Letters Patent. Patented Apr. 16, 1918.

Application filed September 21, 1916. Serial No. 121,455.

To all whom it may concern:

Be it known that I, GEORGE L. TRUESDELL, a citizen of the United States, residing at Redwood Falls, in the county of Redwood, 5 State of Minnesota, have invented certain new and useful Improvements in Low-Tension Spark-Plugs; and I do hereby declare the following to be a full, clear, and exact description of the invention, such as will 10 enable others skilled in the art to which it appertains to make and use the same.

This invention relates to the class of igniting devices for internal combustion engines, and has particular reference to a low 15 tension spark plug.

The primary object of the invention is to construct a spark plug which may be successfully employed upon any gas engine by employing a low tension current and one 20 which will make use of a low tension current even though it is operated on an engine using a very high compression which ordinarily increases the resistance to the passage of the spark across the terminals of 25 the plug of an ordinary make and break system. By providing a successful low tension spark plug, the ignition question in internal combustion engines is greatly simplified in that it makes it possible to use a low 30 tension current which may vary more or less without destroying the effectiveness of the spark, a condition which does not exist in other ignition circuits, since it is necessary in the latter to maintain the strength of the 35 current up to a high degree. As a result, the cost of the operation of a low tension system is a fraction of that which is necessary to maintain a high tension system, since there are fewer parts in the system, 40 and those which remain are of such a character that they seldom get out of order. The timing of the spark is very easily accomplished and can be done while the engine is running, a further advantage rising 45 from the low tension system which my invention makes successful.

With the above object in view and such other objects relative to the construction of the spark plug which will hereinafter appear, my invention will now be fully set forth and described, reference being had to the accompanying drawings.

In the drawings,

Figure 1 is a vertical section,

Fig. 2 is a section on line 2—2 of Fig. 1,

Fig. 3 is a sectional detail; and

Fig. 4 is a further detail.

Referring more particularly to the drawings, 1 indicates a plug member which is preferably made of brass and is threaded to 60 go into the usual plug opening in the head of a cylinder. The plug 1 is provided with a central vertical cavity 2 in the upper portion of the body, and terminates at its lower end in a vertical bore 3 which centrally extends to the lower section of the body. The cavity 2 is threaded to receive a stem 4 of brass or other suitable metal or material, which is provided with a central bore 5 which forms a continuation of the bore 3, the stem 70 4 terminating at its upper end in a flat dish-like receptacle 6 having an upwardly extending annular wall 7. The annular wall 7 is provided with an internal shoulder 8 upon which seats the diaphragm 9 into which is 75 threaded the iron shell 10. The shell 10 forms a housing for the electro-magnetic coil 11 which is wound around an iron core 12. The latter, is secured to the screw 13 which is passed centrally through the end wall of 80 the casing 10, and is threaded into the core 12. The housing 6 is of sufficient depth to permit a disk-shaped armature 14 to reciprocate vertically therein, under the influence of the electro-magnet 11, the armature 14 85 having a stem 15 which extends downwardly through the bores 5 and 3, and terminates at its lower end in a flat tongue 16. The tongue 16 is vertically slotted and receives through the slot a contact finger 17 which is formed 90 of spring metal, and has one end secured to the lower end of the plug 1. The stem 15 is provided within the chamber 6 with a collar 18 which is rigidly mounted upon the stem and receives upon its upper face, the forked 95 ends of a leaf spring 19 whose opposite end is riveted or otherwise secured to the bottom wall of the chamber 6. The spring 19 serves to normally hold the armature in its lowered position, so that the spring contact 17 does 100 not lie against the lower end of the slot in the tongue 16.

The plug 1 is provided at one side of the cavity 2 with a vertical bore 20 in which is fitted the insulated electrode 21 which is held 105 in position by means of the upper lock nut 22 and the lower lock nut 23. At its upper end the electrode member 21 is provided with a second binding screw 24, the lower end of the electrode 21 is overturned and shaped 110

into the contact point 25 which is provided with a platinum tip and opposes the corresponding tipped end of the spring contact 17. The contact 17 and the contact 25 are in normal engagement, and the contact therebetween is broken by means of the stem 15 when the armature 14 is elevated by the electro-magnet 11. As above stated, the spring contact 17 passes through a slot in the lower end of the stem 15, so that when the armature 14 is attracted, the contact 17 is not immediately lifted, but the current through the contact is allowed to build up to a certain degree before the break is made so that the spark will be of suitably heavy character to ignite the charge. The coil 11 is provided with an attachment plug 26 which is preferably entered through the top of the casing 10, and serves to connect the free end of the coil in the ignition system.

The operation of the plug is obvious from the foregoing description, but it should be noted that the various steps of the operation of the plug are carried out in a manner which produces a heavy spark with a low tension current, the peculiar construction of the stem and its connection with the spring contact member permitting the current to attain an appreciable strength so that when the terminals of the contacts are separated, a heavy spark will be the result which is sufficient to ignite the charge in a gasolene engine of large size. Furthermore, this heavy spark will result in spite of the fact that the engine may be of the high compression type. The armature is of a construction which insures the positive opera-

tion of the plug since it is of such area with respect to the power of the plug that its attraction is a strong one and the contacts 17 and 25 will be snapped apart with a violent break. The parts of the plug are easily accessible and since they are few in number and without complication, the plug may be manufactured at a comparatively low cost, and may furthermore be installed upon automobiles without disturbing to any great extent the original wiring system.

What I claim is:—

A low tension spark plug, comprising in combination, a body, a casing surmounting the body, an electro-magnetic coil mounted in the casing and providing a chamber in its lower end, a disk armature operative in said chamber, a stem extending downwardly from the armature and through said body, the lower end of the stem having a vertically elongated loop formed thereon, a rigid contact and a resilient contact in normal engagement with the rigid contact, said resilient contact extending through said loop and normally out of contact therewith, but within the range of the movement of the lower end of the loop so that upon the upward stroke of the stem the resilient contact will be separated from the rigid contact at the end of the stroke of the armature.

In testimony whereof, I affix my signature, in the presence of two witnesses.

GEORGE L. TRUESDELL.
